MANIFOLD FORM

George L. Fulk, Mentor, Ohio, assignor, by mesn.
assignments, to J. Stuart Fleming, Niagara
Falls, N. Y.

Application August 20, 1931, Serial No. 558,271

7 Claims. (Cl. 282—12)

This invention relates to forms for manifolding which consist of a number of superposed record sheets assembled in sets with leaves of carbon paper between them, and to continuous strips of such forms connected end to end to provide a continuous web which may be wound into a roll or folded in a zig-zag manner to form a pack for feeding through a typewriting or other printing machine, the present invention being an improvement upon the invention disclosed in my copending application Serial No. 538,103, filed May 18, 1931.

In my copending application above referred to, I have disclosed a manifold form in which each of the record sheets has a partially severed strip along one edge which forms a readily detachable stub, and the intermediate carbon sheets which have unweakened portions extending across the line of partial severance of the record sheets and which are attached to the stub portions of the record sheets so that the carbon paper sheets are removable with the stub portions of the record sheets and can be pulled out after the required data have been recorded without touching the carbon sheets with the fingers.

In the manifold form disclosed in my copending application, the carbon sheets are shown narrower than the record sheets to permit the record sheets to be gripped independently of the carbon sheets at the side edge thereof opposite the detachable stub portions. It is sometimes desirable, however, that the carbon paper extend the full width of the record paper beneath the portion of the form upon which record data are to be placed, and the present invention provides a form which possesses the advantages of the form shown in the application with respect to the removal of the carbon paper but in which the carbon sheets extend the full width of the form.

Manifold strips or record assemblies ordinarily include superposed continuous strips of record and carbon paper and the duplicate form blanks are printed at regular intervals along the length of the superposed record strips, successive forms being separated by lines of perforation extending through both the record paper and carbon paper, dividing the assembly into sets of record or form sheets with interleaved carbon sheets so that after each individual form has been filled out it may be torn from the strip. Form strips of this character often comprise a considerable number of superposed strips of paper, and in such cases considerable force is required to tear a set of form sheets from the strip and indi-

vidual sheets of a form are often damaged. The present invention facilitates the separation of the individual forms from the strip and lessens the danger of damaging the form sheets while tearing them apart by providing separate leaves of carbon for the individual forms which are held together solely by the record strips which have lines of perforation between successive forms.

A further object of the present invention is to economize in the use of carbon paper by providing carbon paper sheets for the individual forms which are of a size to extend only beneath the portions of the printed blank upon which record data is to be placed.

With the above and other objects in view, the invention may be said to comprise the manifold form and the form strip as shown in the accompanying drawing hereinafter described and particularly set forth in the appended claims, together with such variations and modifications thereof as will be apparent to one skilled in the art to which the invention appertains.

Reference should be had to the accompanying drawing forming a part of this specification, in which

Fig. 1 is a fragmentary plan view showing a portion of a form strip embodying the invention;

Fig. 2 is a fragmentary view showing the perforations separating successive forms of the strip on an enlarged scale;

Fig. 3 is a view showing the manner in which the carbon sheets are detached from the record sheets of an individual form after the form has been torn from the strip;

Fig. 4 is a fragmentary plan view similar to Fig. 1 showing a slightly modified construction; and

Fig. 5 is a view similar to Fig. 3 showing the manner of separating the carbon paper from one of the forms such as shown in Fig. 4.

In Fig. 1 of the drawing there is shown a strip of forms which consists of strips of record paper 1 and sheets of carbon paper 2 interposed between the record sheets of each form. The record paper strips each have a line of partial severance 3 adjacent one side edge which provides a detachable stub portion 4. The carbon paper sheets 2 are unweakened beneath the lines of partial severance 3 of the record paper and the stubs 4 of the record strips are bound together and to the intermediate carbon sheets 2 by suitable means such as staples 5.

In the modification shown in Fig. 1, the carbon paper is assembled with the record paper 55

strips in the form of continuous strips of carbon paper interposed between successive strips of record paper and the carbon paper strips, prior to assembly with the record paper strips, are provided with transverse rows of punched holes 6. The holes 6 are regularly spaced across the strips of carbon paper and the rows of holes are spaced longitudinally a distance corresponding to the length of a form or form sheet. The 10 carbon paper strips may also be provided with cut-out portions 7 at one end of each row of holes 6 for a purpose which will be hereinafter explained.

One or more carbon paper strips are assembled 15 with the record paper strips with the rows of holes 6 registered with respect to the printed matter on the record strips and positioned between successive blanks printed thereon. After the record strips and carbon paper strips have 20 been assembled, transverse rows of perforations consisting of regularly spaced slits 8 are formed through all of the strips. The elongated slits 8 are of a length slightly greater than the space between the holes 6 in the carbon paper and 25 extend between the holes 6 so that, after the slits 8 are made, the holes 6 and slits 8 completely sever the carbon paper strip along each row of perforations, the individual manifold forms or sheet sets of the strip having sheets of 30 carbon paper which are unattached to the sheets of carbon paper of the adjacent forms.

The provision of spaced holes in the carbon paper strip and elongated slits of a length slightly greater than the space between successive holes 35 insures complete severance of the carbon paper, even though there be slight variations in the registration of the slits and holes, so that it is not necessary to maintain extreme accuracy in the feed of the carbon paper and record paper strips 40 during the assembly of the carbon paper and record paper.

The cut-out portions 7 of the carbon paper are on the side edge of the carbon paper opposite that which is attached to the stub portions 45 4 of the record sheets and provide a portion at a corner of the form where the record sheets extend past the carbon sheets, providing a selective grip formation so that the carbon paper can be readily removed with the stubs 4 by gripping the record sheets at a corner of the form 50 opposite the detachable stub with one hand and gripping the stub with the other hand, and then pulling the form apart as illustrated in Fig. 3 of the drawing.

55 In Figs. 4 and 5 of the drawing, there is illustrated a modified form of the invention in which the composite strip or assembly of forms is composed of strips of record paper 11 which have lines of partial severance 12 adjacent one edge, 60 providing detachable stubs 13, and transverse lines of partial severance 14 between successive printed blanks or form sheets, together with interposed sheets 15 of carbon paper extending entirely across the strip and bound to the stub 65 portions 13 of the record strips by suitable attaching means such as staples 16. The leaves 15 are of less length than the printed blanks and are positioned beneath the portions of the printed blanks upon which data are to be recorded. A considerable portion of the printed 70 blank, at the top thereof, is usually occupied by the heading and other printed matter and ordinarily no datum is recorded upon this portion of the record sheet.

75 As shown in Figs. 4 and 5, the carbon paper

leaves are of a length to extend from the bottom of the printed blank to a point below the heading space, leaving a space between successive carbon paper sheets in the strip corresponding to the width of the heading space, thereby effecting 5 a considerable saving in carbon paper.

In assembling the carbon paper with the record paper strip, leaves of carbon paper may be fed laterally between the superposed strips of record paper and attached to the stubs 13 by suitable 10 means such as the staples 16 after they have been inserted.

As shown in Fig. 5 of the drawing, the record paper sheets of an individual form may be instantly detached after the form has been torn 15 from the strip by grasping the detachable stub in the one hand and the opposite side of the form alongside the heading space and above the sheets of carbon paper with the other hand, and pulling, the carbon paper sheets coming out 20 with the stub 13.

It will be observed that in both modifications herein illustrated, successive forms of the strip are held together by tear lines formed in the record paper only and that the carbon leaves 25 of successive forms of the strip are unattached, so that less force is required to tear the forms apart, and there is less danger of damaging or tearing the leaves of the forms.

It will also be observed that in both modifications means is provided for quickly and easily separating the carbon and record paper sheets of the individual forms, without smearing the record paper sheets or soiling the fingers.

Furthermore, it is to be understood that the 35 particular form of apparatus shown and described, and the particular procedure set forth, are presented for purposes of explanation and illustration and that various modifications of said apparatus and procedure may be made without 40 departing from my invention as defined in the appended claims.

What I claim is:

1. A form strip composed of superposed strips of record paper and interposed carbon paper, 45 the form strip having transverse tear lines formed by a row of regularly spaced and aligned elongated slits extending through the superposed strips of record and carbon paper, said carbon paper having holes of a diameter greater than the spaces between adjacent slits in the record paper and positioned to register with said spaces between the slits, whereby the carbon sheets of each form are completely separated from carbon sheets of adjacent forms. 50

2. A manifold record assembly including, in combination, long continuous superposed record strips and interposed transfer paper, said record strips having longitudinally spaced transverse weakened tear lines dividing them into sets of 60 record sheets, each set having a sheet of said transfer paper interleaved in transfer relation with the record sheets, said carbon paper having longitudinally spaced transverse rows of holes respectively in register with said weakened tear lines of the record strips, said weakened tear lines having transversely elongated slits with spaces therebetween, said slits being respectively in register with the spaces between adjacent said holes of the transfer paper, said spaces of the record strip tear lines being respectively in register with the holes of the transfer paper, said slits extending through the superposed record strips and transfer paper and extending entirely across the 65 said spaces between the holes of the carbon paper 70

whereby the transfer sheets of two adjacent sets are completely separated from each other.

5. A method of making a manifold record assembly having a plurality of sets of interleaved record and transfer sheets, which includes: forming a long continuous strip of transfer material with longitudinally spaced transverse lines of holes spaced apart, interleaving long continuous record strips in transfer relation with said transfer strip, and then providing longitudinally spaced transverse lines of partial severance in the interleaved record strips along which the sets of sheets may be severed from the assembly, said lines of partial severance being provided by forming longitudinally spaced rows of slits spaced apart in the superposed record strips respectively in register with the lines of holes of the transfer strip, and at the same time slitting the spaces between the holes in the transfer strip to effect complete severance of two adjacent transfer sheets.

4. A manifold record assembly including, in combination, long continuous superposed record strips having longitudinally spaced transverse lines of partial severance dividing them into a plurality of sheet sets and providing for severance of said sets from the assembly, said record strips having attachment with each other at each said sheet set, and a transfer sheet interleaved in transfer relation with the record leaves of each said set, each transfer sheet of each said set being attached in its set to retain it in transfer position and being separate and independent of the transfer sheet of any other of said sheet sets of the assembly.

5. A manifold record assembly including, in combination, long continuous superposed record strips having longitudinally spaced transverse lines of partial severance dividing them into a plurality of sheet sets and providing for severance of said sets from the assembly, said record strips having attachment with each other at each said sheet set, and a transfer sheet interleaved in transfer relation with the record leaves of each said set, each transfer sheet of each said set be-

ing attached in its set to retain it in transfer position and being separate and independent of the transfer sheet of any other of said sheet sets of the assembly, and said transfer sheets being shorter than the record sheets of the respective sheet sets.

6. A manifold record assembly including, in combination, long continuous superposed record strips having longitudinally spaced transverse lines of partial severance dividing them into a plurality of sheet sets and providing for severance of said sets from the assembly, said record strips having longitudinally disposed weakened severance lines extending along one longitudinal assembly margin and providing a longitudinal severable margin binding strip at which the record strips are bound together at the respective sheet sets, and transfer sheets interleaved in transfer relation with the record sheets of the respective said sets and being bound in said severable marginal binding strip, each said transfer sheet of each set being separate and independent of the transfer sheet of any other of the assembly sets.

7. A manifold record assembly including, in combination, long continuous superposed record strips having longitudinally spaced transverse lines of partial severance dividing them into a plurality of sheet sets and providing for severance of said sets from the assembly, said record strips having longitudinally disposed weakened severance lines extending along one longitudinal assembly margin and providing a longitudinal severable marginal binding strip at which the record strips are bound together at the respective sheet sets, transfer sheets interleaved in transfer relation with the record sheets of the respective said sets and being bound in said severable marginal binding strip, each said transfer sheet of each set being separate and independent of the transfer sheet of any other of the assembly sets, and terminating at one end thereof short of the adjacent ends of the superposed record sheets.
